DESIGN FOR A TEXTILE FABRIC OR THE LIKE

Henry F. Dunbar, Providence, R. I.

Application March 3, 1934, Serial No. 50,937

Term of patent 3½ years

To all whom it may concern:

Be it known that I, HENRY F. DUNBAR, a citizen of the United States of America, residing at Providence, county of Providence, State of Rhode Island, have invented a new, original, and ornamental Design for a Textile Fabric or the like, of which the following is a specification, reference being had to the accompanying drawing forming a part hereof wherein the figure represents a face view of a textile fabric showing my new design.

I claim:

The ornamental design for a textile fabric or the like, substantially as shown.

In witness whereof, I have signed this application.

HENRY F. DUNBAR.
